EARLE E. HOENSTINE, OF ALTOONA, PENNSYLVANIA

JOINT FOR SUPERHEATERS OR THE LIKE

Application filed September 3, 1930. Serial No. 479,518.

My invention relates to joints for superheaters or the like, and has particular relation to ball joints forming the connection between tubes and a header. In using the term 5 "header" herein I mean to include any form of pipe, box or distributing chamber used for conveying a fluid under pressure.

Heretofore it has been proposed to form the ends of superheater tubes for locomotives 10 with enlarged heads having exterior surfaces of substantially spherical contour, these heads being ground into rounded seats adjacent the header openings, so that a yieldable steam-tight connection may be had between the 15 header and tubes. When such tube heads become worn, as the result of continued service or of being frequently re-ground, the tubes are necessarily reduced in length to sizes below the standard dimensions. Accordingly, 20 it becomes periodically necessary either to build up the tube ends by autogenous welding, resurfacing and regrinding the built-up head; or to replace the header; or to cut off the worn ball joint, and to upset or form a new ball end 25 on the tube. The first two methods necessitate a considerable expense and involve obvious difficulties. The third method requires a shortening of the tube to such an extent that the unit when repaired must be applied to a 30 class of locomotives requiring tubes of shorter length.

The object of the present invention is to provide a joint for superheaters designed to eliminate the above recited difficulties attending the repair of worn tube ends. My invention is characterized by the provision of a renewable steam-tight ball joint adapted to be inserted between tube ends and a header, and serving particularly to prevent wear upon the tube ends so that the tubes will not have to be repaired or replaced periodically on account 40 of worn ends, but on the contrary will last indefinitely.

Other objects and advantages characterizing my invention will be more fully apparent from the description which follows herein-after having reference to the accompanying drawing, wherein I have illustrated one embodiment of the invention and certain contemplated modifications as to details.

The drawing represents a cross-section of a part of a header, and a pair of tube ends, one shown in section and one in side elevation, fitted with ball joints of my invention.

The apparatus disclosed in the drawing 53 comprises generally a portion of a header 1 of a locomotive superheater, a pair of tube ends 2 and ball joints 3 fitting between the header and tube ends. Adjacent each opening 4 in the header 1 there is a rounded seat 5 engaged by the spherical portion 6 of a ball joint 3. The means shown for clamping the tube ends 2 to the header comprise rings 7 bearing against expanded portions 8 of the tube ends and a clamp 9 bridging the pair of tube ends and drawn towards the header by screwing nut 20 on bolt 10. However, the particular construction of the header and the means selected for clamping the tube ends thereto form no part of the invention, and 60 obviously admit of considerable variation.

With particular reference to the drawing, it will be seen that each tube 2 is expanded at its end to form a socket 11 having an annular shoulder 12 of a diameter considerably larger than the body of the tube. The inner face of the shoulder 12 is inclined at 13 to an angle of approximately 45° with the axis of the tube, and resting upon this inclined face 13 there is a washer 14 of circular cross section, preferably made of copper, the washer being interposed between the tube end and a right angled shoulder 15 on the ball joint 3, forming a steam-tight seal between these parts. The shoulder 15 of the ball joint 3 defines with the inclined face 13 of the tube end a triangular cavity within which the washer 14 is disposed. It will be apparent that as the tube ends are drawn up towards the header with the washers 14 and ball joints 3 in place, the washers will be squeezed tightly and flattened against the inclined face 13 of the tube ends and the right angle shoulders 15 of the ball joints. Furthermore, while the ball joints 3 are designed to fit within the sockets 11, the presence of the soft metal washers prevents there being any wear on the tube ends. The co-efficient of thermal expansion of copper is greater than that of mild steel, the material of which 65 70 75 80 85 90 95 100

the tubes and headers are customarily made, and under all conditions of temperature the washer maintains a steam-tight joint. Allowances are made in the dimensions of the 5 lower ends 16 of the ball joints 3 so that when the parts are assembled and a considerable pressure, tending to draw the tube ends toward the header 1, is exerted, the washer 14 will be squeezed between the three 10 bearing points on the ball joint and tube socket, and a tight seal will be effected. When pressure is thus applied by screwing the nut 20 on the bolt 10, each soft metal sealing ring 14 is pressed into a three point bearing 15 from which it cannot become dislodged by shifting or by the customary rough usage to which superheater units are subjected in service.

From the above description it will be apparent 20 that the ball joints 3, which are ground when made, and the washers 14 are the only parts which are subjected to wear and these parts may be readily renewed. To replace the ball joints 3 it is not necessary to remove 25 the tubes or any part of the superheater from the locomotive. The renewal of a ball joint 3 may be accomplished by simply unscrewing the nut 20 on the bolt 10, which permits the 30 lowering of clamp 9 and ring 7 with the tube 35 ends 2 a sufficient distance, so that the worn ball joint is clear of the shoulder 12. Accordingly, at repair points it is sufficient that a stock of ball joints and sealing washers be kept on hand, and there is no necessity for 40 making provision for the difficult operations now used in repairing tubes.

The forging and forming of a tube end 45 to the shape described herein can be accomplished with simple dies and forming tools, and the renewable ball joint can be produced at low cost. Furthermore, my invention while eliminating the difficulties now attending the repair of worn tubes, does not involve any change of a radical nature in the 50 superheater as a whole. The invention may be applied to present forms of superheaters without requiring any change in the headers or in the means for clamping the tubes to the headers.

55 While I have described the invention in some detail and with reference to a specific embodiment thereof in a locomotive superheater, it will of course be apparent that various changes in the form of the renewable ball joint and the tube ends may be made without departing from the spirit of the invention as defined in the claim hereto appended.

60 Having thus described my invention, I claim:

In a superheater, a header, a tube leading 65 to said header, said tube having an expanded end forming an annular socket and terminating in an end face inclined to the axis of the tube, a ball joint connection between

said tube and header, said connection fitting within said annular socket and having a substantially right angled shoulder opposite the inclined face of said tube end, and a sealing member of relatively soft metal interposed between the shoulder of said ball joint connection and the inclined face of said tube end.

In testimony whereof, I have hereunto signed my name at Altoona, Pennsylvania, this 20th day of August, 1930.

EARLE E. HOENSTINE.
